ATTORNEY.

UNITED STATES PATENT OFFICE.

LINCOLN B. SHERWOOD, OF INDIANAPOLIS, INDIANA.

AIR-PUMP.

1,076,610.

Specification of Letters Patent. Patented Oct. 21, 1913.

Application filed May 27, 1910. Serial No. 568,703.

To all whom it may concern:

Be it known that I, LINCOLN B. SHERWOOD, citizen of the United States, residing at Indianapolis, in the county of Marion 5 and State of Indiana, have invented certain new and useful Improvements in Air-Pumps, of which the following is a specification.

My invention relates to improvements in 10 air pumps and has for its objects the protection of the valves and packings in the piston, which are preferably of leather and well oiled to give best service, and such as are placed within the oil tank and below 15 level of the liquid therein, and where air pressure is to be pumped into the tank above the liquid, that the said liquid may be forced to a higher level or under pressure to the generator in a soldering furnace, having 20 means provided to shield check valve entirely from the liquid in which the pump may be submerged.

My device is more especially useful in 25 the equipment of a popular soldering furnace, with which I have had a great deal to do, and in which gasoline has always caused the rapid deterioration of the valves and piston packings, with means for shielding the packings and valves in the plunger 30 absolutely from contact with or deterioration caused by the action of gasoline, and I attain these objects by such means as shown in the accompanying drawings and described in the following specification and 35 more particularly pointed out in the claim.

In the different figures of the drawings and throughout the specification, like numerals are employed to point out or refer to like parts and Figure 1 is a side elevation 40 of a gasoline tank in use on a common type of soldering furnace, detached with pump in position; Fig. 2 is a broken side elevation part sectional view of same detached; Fig. 3 is an enlarged partial broken side 45 view of said tank showing pump partly in section and in position; Fig. 4 is a detached broken vertical section of the pump and shield.

Numerical 1 in the different figures represents the tank; 2 the cap of the filler opening; 3 the pipe conducting fuel oil to the burner; 4 shows the depending end of the fuel pipe adapted to conduct all the oil from the tank; 5 is an internally threaded bushing 50 or fitting soldered in upper side of tank and adapted to receive the pump and shield;

6 is the pump cylinder; 7 is the shield surrounding the pump and is of larger diameter than said cylinder providing an annular air space 8 around the pump cylinder and is 60 provided at or near the upper end thereof and at a point within the tank with an air outlet opening 9 communicating directly with the compressed air space 20; 10 is a contracted tubular nipple, the discharge opening from 65 the pump emptying the compressed air from the pump into the air space around the pump and through the port 9 into the compressed air space over the oil within the tank; the said nipple 10 terminates in a contracted surface and is closed by a block of 70 cork or other suitable yielding material 11 which is spring pressed by light springs 12, constituting the check valve.

13 is a knob or handle end of pump piston 75 by which the pump is manipulated.

14 is a screw threaded fitting secured to the pump cylinder near its upper end and is provided at 15 with a thread adapted to screw into the fitting 5, and the threaded 80 section is reduced in diameter to the extent of a few threads at 16 but retaining the same pitch throughout and is adapted to be screwed into the internally screw threaded end of the shield 7 which is provided also 85 at 17 with an externally threaded section of same pitch and equal diameter of thread 15 on part 14 to the extent of two or three threads, whereby the shield may be assembled with the pump and the pump and 90 shield so combined, whereafter they may together be screwed into the tank.

The use of a tank and pump constructed as I have otherwise shown, but without the protecting shield, has been for several years 95 introduced and used quite extensively and in almost all cases where the apparatus has been much used, leaks have developed at the check valve 11, and gasoline was forced from the tank into the pump by static air 100 pressure and the lubricating oil in the leather piston packings was soon dissolved and carried off by the gasoline and the packings would soon become hardened, ineffective and useless and would often have 105 to be renewed, causing delays and expense that have been practically if not entirely eliminated by the application of the protecting shield; another and the worst phase of the rôle of undesirable results possible and 110 often caused by the pump used as applied formerly and without a shield such as I

have here provided, is the danger of overflow of gasolene from upper end of pump, as it will be seen when the pressure is pumped up in the tank and any small solid 5 substance should lodge between the tip of nipple 10 and the check valve, or a sufficient leak from any cause should occur, the pump may soon be filled to overflowing as a few 10 ounces only would be required to fill the pump cylinder when the gasolene would overflow spreading over the tank, and there is then imminent danger of fire from this source.

It is evident that several deviations and 15 alterations might be resorted to without departing from the spirit and scope of my invention to attain like results and I would have it understood that I hold myself at liberty to employ any such alterations and 20 deviations as fall fairly within the spirit and scope of my invention, and

What I claim as new and desire to secure by Letters Patent is,—

An air pump, an externally screw threaded collar secured near upper end of pump 25

cylinder, a screw-threaded section on said collar of two diameters but of equal pitch throughout, the larger diameter joining radial flange of collar, a closed end shield of light metal surrounding said pump, an 30 externally and internally threaded section at open end of said shield, the internally threaded section thereof matching the smaller threaded section on said collar, and the outer threaded section equaling the diameter and meeting the pitch of the larger 35 threaded section on said collar that when the shield is assembled with the pump the external section of thread on said collar and shield present a continuous thread of 40 even diameter and pitch and a tank provided with an internally threaded opening adapted to receive the pump and shield so assembled.

In testimony whereof I affix my signature 45 in presence of two witnesses.

LINCOLN B. SHERWOOD.
